COMBINED LETTER OPENER AND HOLDER FOR STAMPS OR THE LIKE

Harold Charles Dowit, 11835 Sheldon St.,
Sun Valley, Calif. 91352

Filed Oct. 18, 1968, Ser. No. 14,051

Term of patent 14 years

Int. Cl. D19—02

U.S. Cl. D74—5

FIG. 1 is a front elevational view of a combined letter opener and holder for stamps or the like, showing my new design, the back thereof being plain and unornamented.

FIG. 2 is a side elevational view thereof;

FIG. 3 is an exploded elevational view thereof;

FIG. 4 is an enlarged fragmentary portion of FIG. 1;

FIG. 5 is a section taken on the line 5—5 of FIG. 3;

FIG. 6 is a fragmentary section taken on the line 6—6 of FIG. 4;

FIG. 7 is a fragmentary section taken on the line 7—7 of FIG. 4;

FIG. 8 is a fragmentary section taken on the line 8—8 of FIG. 4; and

FIG. 9 is a section taken on the line 9—9 of FIG. 1.

I claim:

The ornamental design for a combined letter opener and holder for stamps or the like, as shown and described.
